UNITED STATES PATENT OFFICE

147,408

DESIGN FOR AN INFANT'S SWEATER

Ena P. Johnson, Abilene, Tex.

Application January 9, 1945, Serial No. 117,358

Term of patent 14 years

(Cl. D3—4)

To all whom it may concern:

Be it known that I, Ena P. Johnson, a citizen of the United States, residing at Abilene, in the county of Taylor and State of Texas, have invented a new, original, and ornamental Design for an Infant's Sweater, of which the following is a specification, reference being had to the drawings forming a part of this application, in which

The characterizing feature of the design consists in the full and outstanding vertical flutes or gathers extending over nearly the entire length of the body and the horizontal flutes or gathers extending over substantially the entire length of the sleeves.

I claim:

The ornamental design for an infant's sweater, as shown.

ENA P. JOHNSON.
